UNITED STATES PATENT OFFICE.

JOSEPH C. CHAPEK, OF MICHIGAN, NORTH DAKOTA.

MANURE-CARRIER.

1,205,855.

Specification of Letters Patent. Patented Nov. 21, 1916.

Application filed April 6, 1916. Serial No. 39,403.

To all whom it may concern:

Be it known that I, JOSEPH C. CHAPEK, a citizen of the United States, residing at Michigan, in the county of Nelson and State of North Dakota, have invented new and useful Improvements in Manure-Carriers, of which the following is a specification.

This invention relates to manure carriers especially adapted to be used in barns or similar structures for transferring the manure from the stable in order that it may be dumped into a spreader and it consists in the novel features hereinafter described and claimed.

The structure includes a wheel mounted frame upon which is positioned a body having a bottom composed of hinged panels. Pulleys are arranged at the side of the frame and other pulleys are mounted upon the body. Rollers are journaled at the side of the body and a chain or other flexible element is trained under the said rollers and connected at their ends with the hinged panels and the intermediate portion of the said chain or flexible element is trained around the said pulleys. A lever is fulcrumed upon the body and carries a pulley around which the intermediate portion of the said chain or flexible element is trained. When the lever is swung from a vertical to an approximate horizontal position the said chain or flexible element is drawn whereby the hinged panels are moved to closed position in the bottom of the body and when the said lever is swung so that it is vertically disposed the said chain or flexible element is moved longitudinally whereby the said bottom panels under the influence of gravity may swing to open position and the contents of the body may gravitate therefrom.

In the accompanying drawing:—Figure 1 is a side elevation of the manure carrier. Fig. 2 is a transverse sectional view of the same. Fig. 3 is a fragmentary longitudinal 45 sectional view of the same.

The manure carrier comprises a frame 1 which is mounted upon wheels 2 in any suitable or usual manner. The said wheels are arranged to travel along track rails 3 which 50 may be positioned upon the floor of a barn or any other suitable support and which may extend if so desired beyond the side of the barn. A body 4 is mounted upon the frame 1 and the said body is provided with hinged panels 5 which constitute the bottom 55 of the said body. Rollers 6 are journaled

at the side of the body 4 in the vicinity of the ends thereof and openings 7 are provided in the side of the body below the said rollers. Pulleys 8, 9 and 10 are journaled at the side of the frame 1. Pulleys 11 and 12 are journaled at the side of the body 4 above the rollers 6. A lever 13 is fulcrumed at the side of the body 1 and carries at its working end a pulley 14. A chain or other flexible element 15 is connected at its ends with the panels 5 at points between the hinged and free edges thereof, the end portions of the said chain or flexible element then pass through the openings 7 and under the rollers 6 thence over the pulleys 11 and 12. One end portion of the said chain or flexible element extends from the pulley 12 under the pulley 10 and thence over the pulley 14 and under the pulley 9 and along the frame 1 and under the pulley 8. From the pulley 8 the said chain or flexible element extends up to and over the pulley 11 as shown in Fig. 1 of the drawing.

In operation the carrier is used as follows:—The material is loaded into the body 4 of the carrier when the power end of the lever 13 is at a lowered position. When the lever is in this position the chain or flexible element 15 is drawn longitudinally whereby the end portions of the said chain or flexible element hold the bottom panels 5 in closed position in the body 4. When it is desired to dump the material from the carrier, the carrier is moved along the track 3 to any desired point and then the power end of the lever 13 is swung in an upward direction whereby the chain 15 is rendered slack and the chain moves longitudinally about the pulleys 9, 10, 8, 12 and 11 and under the rollers 6 and through the openings 7 whereby the free edges of the bottom panels 5 may swing in a downward direction and the material which was previously supported upon the said bottom panels may gravitate from the bottom 4 and fall into a manure spreader or other receptacle provided for the reception of the material. After the carrier has been dumped the bottom panels 5 are swung to a closed position in the body 4 by swinging the power end of the lever 13 to a lowered position.

From the foregoing description taken in conjunction with the accompanying drawing it will be seen that a manure carrier of simple and durable structure is provided and that the same may be easily and quickly ma-

nipulated to permit the contents thereof to gravitate from the body which normally holds the said contents.

Having described the invention what is claimed is:—

A carrier comprising a wheel mounted frame, a body mounted upon the frame and having hinged bottom panels, rollers journaled at the side of the body, the said body being provided with openings located below the rollers, pulleys mounted upon the body,

other pulleys mounted upon the frame, and a lever fulcrumed upon the body and having at its working end a pulley and a chain trained around the said pulleys and the said rollers.

In testimony whereof I affix my signature in presence of two witnesses.

JOSEPH C. CHAPEK.
